UNITED STATES PATENT OFFICE.

OTTO H. JENSEN, OF BUFFALO, NEW YORK, ASSIGNOR TO THE REPUBLIC METALWARE COMPANY, OF BUFFALO, NEW YORK, A CORPORATION OF NEW YORK.

BEADING-MACHINE.

1,344,405.

Specification of Letters Patent. Patented June 22, 1920.

Application filed September 26, 1917, Serial No. 193,375. Renewed May 17, 1920. Serial No. 382,080.

To all whom it may concern:

Be it known that I, OTTO H. JENSEN, a citizen of the United States, residing at Buffalo, in the county of Erie and State of New York, have invented new and useful Improvements in Beading-Machines, of which the following is a specification.

Sheet metal pot covers are commonly beaded at their edges and provided in their central portions with slots or perforations for receiving the attaching clips of the usual folding handles. It is also customary to stamp or print upon them the name or trade-mark, or both, of the manufacturer.

The object of my invention is the production of an automatic machine by which these several operations are performed successively and expeditiously, with a view of materially reducing the cost of manufacture of such covers.

A further object is to so organize the machine that it can be readily adjusted to operate upon covers of various sizes.

In the accompanying drawings:

Figure 1 is a top plan of a cover beaded, perforated and printed by the machine. Fig. 2 is a transverse central section of the completed cover. Fig. 3 is a side elevation of the machine. Fig. 4 is a rear elevation of the machine, partly in section. Fig. 5 is a transverse section of the beading chuck on line 5—5, Fig. 12. Fig. 6 is a similar section of the perforating and printing dies on line 6—6, Fig. 12. Fig. 7 is an enlarged vertical section of the beading chuck, showing a cover partly beaded. Fig. 8 is a front view of the machine, partly in section. Fig. 9 is a fragmentary sectional elevation of the actuating cam of the beading roller. Fig. 10 is a horizontal section on line 10—10, Fig. 8. Fig. 11 is a top plan view of the means for rocking the cover-carriers to release the covers. Fig. 12 is a vertical longitudinal section of the machine. Fig. 13 is a vertical section, on an enlarged scale, on line 13—13, Fig. 10. Fig. 14 is a top plan view of the machine, partly in section. Fig. 15 is a fragmentary transverse section on line 15—15, Fig. 14. Fig. 16 is a fragmentary longitudinal section on line 16—16, Fig. 15. Fig. 17 is an enlarged longitudinal section of one of the finger-heads. Fig. 18 is a cross section thereof.

Similar characters of reference indicate

corresponding parts throughout the several views.

In its general organization, the machine comprises a horizontal feed table for the cover-blanks, a rotary chuck and a co-operating beading roller arranged to receive the cover blanks successively from said table and bead their edges, perforating and printing dies arranged to receive the beaded covers from said chuck, and traveling cover-supports or carriers for conveying the cover-blanks from said table to the beading devices and said dies and finally discharging the completed covers from the machine.

1 indicates the stationary main frame of the machine which is preferably in the form of a hollow rectangular casing or pedestal and 2 is the main driving shaft of the machine arranged transversely in the frame and having a driving pulley.

Supported at the head of the machine by 75 a bracket 4 or other suitable means, is a horizontal feed table 7 upon which the cover-blanks 8 are successively placed by the operator. This table is somewhat narrower than said blanks so that they overhang it, 80 as shown by dotted lines in Fig. 14. This table may be provided near its front end at opposite sides with a pair of gages 9 for properly positioning the blank thereon, these gages being adjustable toward and 85 from the center of the table to suit different sized blanks. In the construction shown, the gages are mounted on a pair of horizontal rods arranged radially of the table and to which they are adjustably clamped by 90 set screws 11^a or other suitable means.

Located on opposite sides of the feed table and extending lengthwise of the machine, are a pair of parallel rods or carriers 12 which reciprocate in bearings 14 carried by 95 arms 17 projecting from laterally-movable carriages 18 each of which carries one of the rods 12. These carriages slide in transverse guides 19 arranged on the bed of the main frame and are adjustable toward and 100 from each other to adapt the machine to different sized covers, as hereinafter more fully described. In the construction shown, the carriages are simultaneously adjusted by a rotary transverse screw 20 having right 105 and left threads which respectively engage correspondingly threaded lugs 21 depending from the carriages, as best shown in Figs.

15 and 16. This adjusting screw had a hand wheel 22 for turning it. The carrying rods 12 are reciprocated in unison and provided on opposite sides of the feed table 3 with cover-supports, fingers or holders 23 traveling therewith and adapted to carry the cover-blanks from the feed table to the beading mechanism. In the construction shown, each of said rods is provided with 10 a pair of such fingers which stand opposite the central portion of the feed table when the rods 12 are at the extremity of their return stroke, as shown in Fig. 14.

Any suitable means may be employed for 15 actuating the carrying rods 12. The mechanism shown in the drawings for this purpose comprises a reciprocating gear rack 24 arranged below the bed of the main frame lengthwise thereof and traveling in fixed 20 guideways 25 carried by upright guides or bearings 26, 27, secured to said frame. This gear rack is actuated by a grooved rotary cam 28 which engages an anti-friction roller 29 carried by the rack, as shown in Fig. 12. 25 This cam is secured to a countershaft 30 driven from the main shaft by gears 31, 32, as shown in Fig. 3. 33 indicates a pair of heads or slides secured to the carrying rods 12, respectively, and guided upon the laterally-movable carriages 18, as shown in Figs. 14 and 15. These slides are provided with longitudinal rails 33^a which run upon supporting rollers 33^b mounted on the arms 17 of the carriages 18. Secured to the undersides of these slides are longitudinal rack bars 34 which engage gear wheels 35 secured to a transverse shaft 36 journaled in the carriages 18 and connected with the lower gear rack 24 by a suitable gear train 38-42. 40 In the arrangement shown, the shaft 43 of this gear train is hollow and is concentric with the carriage-adjusting screw 20, which latter passes freely through it.

In addition to their reciprocating motion, 45 the carrying rods 12 are capable of a rocking or oscillating motion in their bearings for the purpose of opening or closing the carrying fingers to engage or clear the cover-blanks placed on the feed table, *i. e.* to spread the 50 opposing pairs of fingers on the return stroke of said rods and cause them to approach and engage under the blank on the table and deliver it to the beading mechanism on the effective stroke of said rods. 55 This rocking action is preferably effected by a pair of hollow arms 44 extending inwardly from said rods and a pair of links 45 which slide freely therein and are pivoted at their inner ends to the upper end of a slide- 60 rod 46 by a horizontal pin 47, as seen in Figs. 8, 11 and 12. This rod moves vertically in a fixed guide 48 and is actuated by a rotary cam 49 keyed to the countershaft 30. This cam is constructed to rock the carrying rods 12 outwardly on their return stroke and inwardly

on their effective stroke, thus opening and closing the carrying fingers accordingly.

As shown in the drawings, these fingers are provided at a short distance from their inner ends with beveled stops or shoulders 70 50 which center the cover-blanks on the feed table.

Preferably, the fingers are adjustable toward and from the feed table as well as lengthwise thereof to adapt them to cover-blanks of different sizes. For this purpose, there is fixed to each rod 12 a standard 51 carrying a head 52. This head is provided with transverse grooves or seats 53 in any one of which the shanks of the fingers may 80 be placed, and in which they are retained by a cover 54 removably fastened to the top of the head. Each pair of fingers may also be adjusted toward and from the feed table by a gear pinion 55 mounted on a 85 shaft journaled in the corresponding head and engaging teeth 56 of the fingers, the shaft of the pinion having an external knob 57 for turning it.

Arranged a short distance beyond and in line with the feed table is the cover-beading mechanism which is preferably constructed as follows:

58 and 59 indicate the upper and lower disks or members of a rotary chuck between 95 which the cover-blank is adapted to be clamped and by which it is rapidly rotated while in contact with a grooved horizontal beading roller 60 co-operating with the chuck. The upper chuck-member 58 is removably secured to the lower end of a rotary spindle 61 carried by a standard 62 rising from the bed of the machine, this shaft having a pulley 63 which is suitably driven from the main shaft 2. The lower 105 chuck-member 59 is removably supported upon the upper end of a vertically-movable plunger 64 preferably by a ball bearing 65. This plunger slides in the front guide 26 and is elevated by a cam 66 mounted on the 110 countershaft 30, the downward movement of said lower chuck-member being effected by gravity. As shown in Figs. 6 and 12, the opposing faces of the upper and lower chuck-members are shaped to conform to the 115 cover-blanks, and they are of the proper diameter to allow the rim of the cover to project beyond them, as shown in Fig. 7. The beading roller 60 is arranged adjacent to the edge of the upper chuck-member and mounted on the front arm of a horizontally- 120 swinging lever 67. The rear arm of this lever carries an anti-friction roller 68 which is engaged by a vertically-movable wedge or cam 69, which on its upward stroke forces 125 the beading roller against the projecting rim of the cover, beading the same. This cam is formed at the upper end of a vertical rod or plunger 70 sliding in a guide 71 carried by the standard 62 and actuated by a 130

grooved rotary cam 72 keyed to the counter-shaft 34, as shown in Figs. 9 and 12. A spring 73 attached to the rear arm of the lever 67 serves to swing it in the proper direction to withdraw the beading roller to its inoperative position. To adapt the beading roller to covers of different sizes, its carrying lever is made adjustable toward and from the beading chuck. For this purpose, the lever pivot or fulcrum-pin 74, Figs. 10 and 13, is preferably carried by a slide or follower 75 guided in a groove 76 in the underside of the lever-bracket 77. The lower portion of the fulcrum-pin which 15 extends below the bracket carries the lever, while the upper portion of the pin passes through a longitudinal slot 78 of the bracket and is provided with a lock nut 79 for retaining it in position. The fulcrum pin is 20 adjusted in this slot by a rotary screw 80 held against longitudinal movement in said bracket and engaging a threaded opening in the follower 75.

As the upper chuck-member 58 rotates 25 constantly during the operation of the machine, the lower member on receding from it would continue to spin and be liable to throw the beaded cover off by centrifugal force, in the absence of some means to stop 30 such rotation. The device shown in the drawings for this purpose consists of a brake or brake disk 81 arranged underneath the lower chuck-member 59 and loosely encircling its hub, as shown in Fig. 12. This 35 brake disk is carried by the forked front end of a vertically-swinging lever 82 fulcrumed on a bracket 83 depending from the feed table 7 or other suitable support. The forked end of this lever is constantly urged 40 upward by a spring 84 connected to its rear arm, the upward movement of the brake-lever being limited by a stop 85 arranged 45 to be encountered by the rear arm of the lever. Upon the ascent of the lower chuck-member, the spring 84 causes the brake disk to follow it up until the cover nearly touches the upper chuck-member, when the brake disk is arrested by the stop 85, thereby allowing the lower member and the cover to 50 rotate freely with the upper member. Immediately after the lower member begins its descent and before the chuck-members become separated sufficiently to release the beaded cover, the lower member comes in 55 contact with the brake disk which promptly arrests its rotation, preventing the cover from flying out of the chuck.

A weight 85^a is preferably employed to hold the cover-blanks upon the lower chuck-member while the latter rises and descends. This weight is attached to the lower end of a guide-rod 85^b which slides in the spindle 61. The upper chuck member is provided in its face with a recess 85^c which receives 60 said weight and allows the cover blank to 65 bear fully against said face.

Adjacent to the beading chuck the carrying rods 12 are provided with a second set of supporting fingers 86 similar to the fingers 23 which engage under the beaded edge 70 of the cover on the return stroke of said rods and carry it onward between the perforating and stamping dies on the next effective stroke of the rods. 87, 88 indicate the male and female members of these dies 75 which are formed to produce the desired imprint upon the covers, such as the manufacturer's name and trade-mark. In addition to such lettering, the upper die 88 is provided with punches 89 for forming the 80 desired slots or apertures in the cover to receive the usual clips of the handle, the lower die being provided with corresponding recesses 90 to receive the punches. The stationary upper die is secured to a standard 85 91 mounted on the bed of the machine, while the relatively movable lower die is carried by a plunger 92 sliding in the rear guide 27 and actuated by a cam 93 mounted on the countershaft 30, as shown in Fig. 12. Associated with the upper die member is a 90 spring-pressed stripper 94 of ordinary construction.

Located opposite the dies is a third set of 95 supporting fingers 95 mounted on the carrying rods 12 and adapted to convey the printed and perforated covers from the dies to a receptacle or suitable place of delivery at the rear end of the machine. Like the first and second sets of fingers, those of the third 100 set clear the covers during the return stroke of said rods and carry them onward upon the effective stroke of the rods.

The operation of the machine is as follows: 105

Power being transmitted to the main driving shaft 2, the carrying rods 12 are reciprocated as before described, their stroke being equal to the distance between the centers of the beading chuck and the dies. 110 Upon now placing a cover blank on the feed table 7, the first set of fingers 23 advance it to a position directly over the lower chuck-member 59, which thereupon rises and presses the cover-blank against the rotating upper chuck-member 58. As soon as the blank reaches this position, the beading roller 60 is forced against its edge by the cam 69, beading the same in an obvious manner. Immediately after the beading operation, the lower chuck-member recedes from the upper one and deposits the beaded cover upon the second set of fingers 86, which in the meantime have been brought to their initial position and swung inwardly 115 to support the cover. The rods 12 now again move rearwardly, carrying the beaded cover between the dies 87, 88, which 120 125

thereupon perforate and print the cover by the elevation of the lower die. During the last-named operation, the third set of fingers 95 which had previously been moved 5 rearwardly beyond the dies, return to a position opposite the dies ready to receive the printed and perforated cover and upon the next effective stroke of the rods 12 these fingers carry the cover beyond the dies to the 10 place of delivery where they are withdrawn by the rocking action of said rods, releasing and dropping the cover.

The cover-carriage composed of the carrying rods 12 and the several sets of fingers, 15 comes to a standstill at both ends of its stroke while the beading and perforating and printing operations are taking place.

It will be understood from the foregoing that a plurality of covers or blanks are 20 constantly passing through the machine and automatically beaded, perforated and printed, it being only necessary to feed the blanks to it by hand, which can be done by unskilled labor.

25 It follows that by the use of this machine, the manufacture of such covers is greatly expedited and their cost considerably reduced.

The machine moreover, can be adapted 30 to different sized covers by substituting larger or smaller chuck-members 58, 59, for those shown, and adjusting the beading roller 60 accordingly, as hereinbefore described.

35 The carrying rods 12 are also adjusted toward or from each other for this purpose by means of the right and left screw 20, the principal or coarse adjustment being effected by this screw, while the finer 40 adjustment is effected by shifting the carrying fingers by means of the pinions 55.

The speed of the carrying rods is the same for various sized covers, but the speed of the beading chuck is preferably varied according 45 to the diameter of the covers, being higher the greater their diameter. Any suitable speed changing gearing may be employed for this purpose. In the drawings, only a part of this gearing is shown at 96, 50 97 and 98.

While this machine is designed more particularly for beading, perforating and printing pot-covers, it may obviously be used for producing other articles of a similar character.

I claim as my invention:

1. In a machine of the character described, the combination of a carrying mem-

ber, a head mounted thereon and having a groove, a supporting finger guided in said groove and having gear teeth, and a rotary adjusting shaft journaled in said head and having a pinion meshing with said teeth.

2. In a machine of the character described, the combination of a carrying member, a head mounted thereon and having a series of transverse grooves, a removable supporting finger adapted to occupy one or another of said grooves to adjust it lengthwise of said head, said finger having a series of gear teeth, and being also adjustable crosswise of said head, and an adjusting shaft journaled in said head and having a pinion meshing with said finger and co-extensive with said series of grooves.

3. In a machine of the character described, the combination of a chuck comprising an upper rotary member, a vertically-movable plunger arranged beneath the same, a lower chuck-member rotatably mounted on said plunger, means for intermittently elevating said plunger, a brake arranged to arrest rotation of said lower chuck-member upon receding from the upper one, means for causing said brake to follow the ascent of the lower chuck-member, and a beading roller coöperating with the chuck.

4. In a machine of the character described, the combination of a chuck comprising an upper rotary member and a lower vertically-movable member arranged to receive blanks between them, means for intermittently moving said lower chuck-member toward the upper one, a brake for arresting rotation of said lower chuck-member upon receding from the upper one, a spring tending to move the brake against the lower chuck-member as the latter rises, and a stop arranged to arrest the upward movement of the brake.

5. In a machine of the character described, the combination of a chuck comprising an upper rotary member and a lower vertically-movable member arranged to receive blanks between them, means for intermittently moving said lower chuck-member toward the upper one, a brake-disk for arresting rotation of said lower chuck-member upon receding from the upper one, a lever carrying said disk, a spring connected to said lever and tending to move the brake-disk upwardly, and a stop arranged in the path of said lever to arrest the ascent of the brake-disk.

OTTO H. JENSEN.
